ABSTRACT OF THE DISCLOSURE

The invention is directed to a bag, suitable for use as a vacuum cleaner filter bag, comprising a sheet of flexible material having a pair of opposing side edges, one of said side edges being provided with a plurality of pleats, including a face pleat, formed thereon, the other side edge being provided with a face panel, said sheet being transversely folded medially of its length, the confronting face panels being joined together, so that a bag is formed which is resultingly off-centerly expandable.

BACKGROUND OF THE INVENTION*Field of the invention*

This invention relates generally to a bag and more particularly to an expandable bag for use as a disposable vacuum cleaner filter bag.

Description of the prior art

Conventionally, a disposable type vacuum cleaner filter bag comprises a bag formed of a flexible air pervious filter material capable of performing the separating operation in order to remove the dust and debris from the air stream in which it is entrained. The bag must be capable of withstanding the strain imposed thereon during the operation of the suction cleaner, as well as the weight of the waste material entrapped therein.

In order to promote the efficiency of this type bag, it is highly desirable that a maximum filter surface area be presented in order to accomplish the separation function. Moreover, in order to reduce the requirement of frequent replacement and also to reduce the cost of the same, it is highly desirable that the bag or receptacle present as large a volume, for receiving the waste material, as possible.

An additional feature found to be desirable in vacuum filter bags is that such bag conform itself as closely as possible to the configuration of the housing or receptacle within which it is disposed during use, in order to utilize the available space at maximum efficiency. This requirement has become increasingly important in view of the tendency to reduce the overall size of the vacuum cleaning apparatus and the often asymmetrical configuration of the space within which the bag is disposed. The desire for compactness often results in a design wherein the configuration of the space provided for the bag does not conform to conventional bag shapes and may include projections in the interior of the bag receiving compartments which require substantial distortion of the bag shape, particularly when distended in use.

SUMMARY OF THE INVENTION

It is therefore among the principal objectives of this invention to provide a bag having the aforesaid desirable features.

In accordance with the present invention there has now been provided a bag, suitable for use as a vacuum cleaner filter bag, comprising a sheet of flexible material having a pair of opposing side edges, one of said side edges being provided with a plurality of pleats, including a face pleat,

2

formed thereon, the other side edge being provided with a face panel, said sheet being transversely folded medially of its length, the confronting panels of the face pleat and face panel being joined together, said pleats being laterally distensible along said transverse fold, whereby a bag is formed which is resultingly off-centerly expandable. In order to form the vacuum cleaner filter bag, the confronting pleated ends and opposing face panel ends of said sheet are folded over upon themselves to thereby secure said pleats against lateral displacement along that end of the bag, the pleated edges being held in pleated condition only by the bight along said transverse fold at the other end of the bag.

BRIEF DESCRIPTION OF THE DRAWINGS

The invention will be hereinafter more fully described with reference to the accompanying drawing in which:

FIGURE 1 is a perspective view of the invention vacuum cleaner filter bag in completed form.

FIGURE 2 is a view in cross-section taken along line 2—2 of FIGURE 1.

FIGURE 3 is a view in perspective of the subject filter bag except that the bag is shown in the expanded condition, as by mounting in a suitable vacuum cleaner and connected to the air-inlet thereof, the air-inlet being shown by phantom lines.

FIGURE 4 is a reduced, fragmented view in perspective of the blank, from which the bag comprising the invention is formed, in the process of being folded over to form a folded bottom for the bag.

DESCRIPTION OF THE PREFERRED EMBODIMENTS

Referring now to the figures of the drawing, the bag in accordance with the present invention is off-centerly expandable and is formed of a blank 10 (FIGURE 4), said blank comprising an elongated sheet of material, such as flexible porous paper, normally employed for disposable filter bags, and having opposing longitudinal side edges 12 and 14. Side edge 14 has an inwardly directed face panel 16, while side edge 12 is formed into a plurality of pleats 20, 22, 24 and 26 by means of re-entrant folds which rest against flat body 30 of the blank. The apices 21, 23, 25 and 27 of the respective pleats extend along the side edge 12 of the blank in step-wise fashion, with the shortest marginal extension being at apex 21 and the longest at 27, 23 and 25 being intermediate thereof, 25 being longer than 23, for a reason to be further explained. Face panel 32 of face pleat 26 is inwardly directed and is of a narrower width than side pleat 26. The exposed surfaces of face panels 16 and 32 have deposited thereon longitudinally extending adhesive stripes 34. As shown in FIGURE 4, the blank 10 is folded upon itself, along transverse fold line 36 medially of the length of the blank, so that the respective halves of the blank are brought into confronting relationship and form opposing flat face walls 38 and 40 for the bag structure. Adhesive contact is made between the opposing halves of the exposed surfaces of the said face panels so that there is thus formed a bag structure having a folded bottom end and an open mouth at its terminal end. This can readily be seen by referring to FIGURE 4 wherein the blank 10 is shown folded upon itself and when the adhesive stripes 34 make contact, a bag is formed having an open mouth, as aforesaid. By viewing FIGURE 2, especially, it can be seen that pleats 20, 22, 24 and 26 form gussets 42, 44 and 46, respectively. The bag is readily expandable by manually grasping, if desired, the pleat edges 50. This action causes the pleated side to unfold and open thereby, laterally off-centerly extending the bag wall to form a relatively large bag of generally right-triangular configuration.

When the bag is intended for vacuum cleaner use, in a preferable embodiment of the invention, opening means 60 (FIGURES 1 and 3) are provided in one of the face walls as wall 38. Opening means 60 are effected by means of a plurality of cuts 62 in said wall 38, which cuts generally conform to a star-shape, the lines of said cuts intersecting in the approximate center of said means 60. The opening means 60 are surrounded by a collar 64 to provide a suitable mounting means for the air-inlet (phantom lines), fitting of a suitable vacuum cleaner (not shown) and to provide access into the interior of the bag. The open end 66 of the bag is completely sealed by providing transverse adhesive stripes 68, 70, 72 and 74 on the open end so that when the top edge thereof is twice folded over upon itself as shown at 76 in FIGURE 1, said end of the bag is completely sealed and the terminal portions 78 of the pleats and opposing side edge 14 are interfolded and thereby confined against displacement or unfolding movement in a lateral direction, such sealing being accomplished by known conventional means. It will be noted, however, that the pleats along the folded bottom 80 of the bag are retained only by the bight of the transverse fold 36, so that they are thus adapted to be expandable.

When the vacuum cleaner filter bag 82 is placed into a suitable vacuum cleaner (not shown) the bag may be manually distended, as aforementioned, which is preferable; however, this is not necessary since the bag is automatically distended by the force of the dirt-laden air entering the interior thereof, as shown in FIGURE 3, in the direction of the arrows, by means of air-inlet 84. Thus, the bag 82 has the ability to conform itself to the interior configuration of the vacuum tank. As shown in FIGURE 3, gussets 42, 44 and 46 are still defined, however, it is clear that when the bag substantially balloons out, that these would substantially disappear. With regard to the stepwise graduation of apices 21, 23, 25 and 27 (mentioned above) this provides for easier manual and/or automatic distension of the off-center expansion capacity of the bag 82.

Having thus described the invention as applied to specific embodiments, it is to be understood that various changes may be made by those skilled in the art without departing from the spirit and scope thereof.

What is claimed is:

1. A disposable vacuum cleaner filter bag comprising a sheet of flexible material having a pair of opposing side edges, one of said side edges being provided with a plurality of pleats, including a face pleat, formed thereon, the other said side edge being provided with only a face panel, said sheet being transversely folded medially of its length, the resulting confronting panels of the face

pleat and face panel being respectively joined together, said pleats being laterally distensible along said transverse fold, the confronting pleated ends and opposing face panel ends of said sheet being folded over upon themselves thereby securing said pleats against lateral distension along that end of said bag, the pleated edges at the other end of said bag being only foldingly secured, whereby said bag is resultingly adapted to be off-centerly expandible.

2. A bag according to claim 1 wherein the apices of said pleats extend outwardly in graduated stepwise relationship with the apex of said face pleat extending the furthest.

3. A bag comprising a sheet of flexible material having a pair of opposing side edges, one of said side edges being formed into a plurality of re-entrant folds disposed against the flat body of the sheet to provide pleated side edges therefor, said pleated edges including a face panel, the other side edge being provided with only a face panel, the exposed surfaces of said face panels having an adhesive substance applied thereto, said sheet being folded upon itself along a transverse fold line medially of its length, the respecting halves of said sheet and face panels being in confronting relation, and being adhesively secured respectively to each other, the pleated side edges of said sheet being only foldingly secured along said fold line, said bag thereby being adapted to be off-centerly expandible.

4. A bag according to claim 1 wherein said face panels are inwardly directed.

5. A bag according to claim 3 wherein said face panels are inwardly directed.

6. A bag according to claim 3 wherein said pleated edges extend outwardly in graduated stepwise relationship with the edge formed by the face panel extending the furthest.

7. A bag according to claim 1 wherein said pleats form a plurality of gussets.
